UNITED STATES PATENT OFFICE

ALBERT DE BOIS SHROSBREE, OF COLD ASH, NEAR NEWBURY, AND EJNAR ALEXANDER ROON BYSKOU, OF BARNEHURST, ENGLAND, ASSIGNEES TO BYSKAN GLAZING LIMITED, OF WESTMINSTER, ENGLAND

GLAZED FRAME

Application filed August 7, 1931, Serial No. 555,668, and in Great Britain September 18, 1930.

The invention relates to that kind of glazed frame which is used in the interior of buildings, as forming part of a door or partition and which may be used as a sash, in which 5 the outer frame and the sash bars are made of metal. To render the same fireproof it is necessary for such frames to be made without solder and with the metal in contact with the sheets of glass which are thick, not only 10 around all the edges of each pane, but also against the two faces thereof. Such a construction renders the glazed frame more rigid and waterproof and improves the appearance thereof.

15 The object of the present invention is to form such a frame in a cheap and efficient manner which will render the same fireproof rigid and waterproof.

According to the present invention the sash 20 bars are of I shape in cross section with straight flanges and all the grooves in the sides of the bars fit the glass to be used therewith around the edges of each pane and on both faces thereof. One set of sash bars is 25 narrower than the other set due to its having thinner flanges, although the grooves for the glass are the same in both sets. As the grooves are the same in both sets of bars it follows that the flanges on the wider bars 30 are thicker than the flanges on the narrower bars. The wider bars are cut away to fit the narrower bars and to allow these latter to be passed therethrough, and the portion cut away partly enters into the thicker side 35 flanges of the wider bar.

The metal frames for use with such sash bars are of channel shape and have three flat sides at right angles to each other which fit 40 two sides of the sash bars and the ends thereof. The channels may be turned inwards along their open side for a short distance and the sash bars are grooved through their flanges and the flanges of the wider bars are 45 partly cut away so that the sash bars may be slid into position in the frame from an open

end of one side of the frame members or may be forced into position by causing the sides of the channel to spring open.

Instead of employing two sets of I shaped bars as above described, one set of the bars, 50 the narrower one, may be I shaped with straight flanges and the other and wider I bars may be have curved flanges instead of straight flanges. These curved flanges are 55 curved towards each other and the webs and the edges of these curved flanges are cut away to fit and to allow the narrower I shaped bars to be passed therethrough. When employing wider bars having curved flanges the two 60 outer curves fit at their edges against the flat outside edges of the narrower sash bars.

The channel shaped frame may be made up in any suitable manner.

The channel shaped frame may be formed by cutting V shaped pieces out of the channel which will allow adjoining parts to be 65 bent up at right angles to each other. In some cases one side and parts of two other sides are thus bent up out of a single piece of channel. A second piece of channel is 70 similarly bent up and the two pieces are connected together by means of liners which accurately fit into the open ends of the part sides.

The invention is illustrated in the accompanying drawings in which:

Fig. 1 is an end elevation of one of the wider sash bars and Fig. 2 is an end elevation of one of the narrower sash bars.

Fig. 3 is a side elevation of a wider sash 80 bar with an aperture cut therein.

Fig. 4 is a plan of two of the sash bars crossing each other.

Fig. 5 is a section of a portion of the frame to carry the sash bars.

Fig. 6 shows a modified form of the wider sash bar, in section, with a narrower sash bar passing therethrough.

Fig. 7 is a side elevation of one of the wider sash bars shown in Fig. 1, which has been 90

machined ready to be inserted into the frame shown in Fig. 5.

Fig. 8 is a similar view to Fig. 7 showing a narrower sash bar.

Fig. 9 is a front elevation showing one construction of a frame partly broken away and with sash bars inserted therein.

Fig. 10 is a side elevation of part of the channel employed to make the frame shown in Fig. 9.

Fig. 11 is a section through part of the frame showing one of the wider sash bars in position therein.

Fig. 12 is a section through part of the frame showing a narrower sash bar inserted therein.

Fig. 13 is a section of the frame on the line 13—13 of Fig. 9 with a connecting liner therein.

Fig. 14 is a side elevation of the wider sash bar shown in Fig. 6.

As shown in Figs. 1 and 2 the sash bars are of I shape in cross section. The bar shown in Fig. 1 has a web 1 and side flanges 2, 2. The sash bar shown in Fig. 2 has a web 3 and side flanges 4, 4. It will be noticed that the flanges 2, 2 are thicker than the flanges 4, 4 and that the grooves 5, 5 in the sides of the bars, to receive the glass, are equal in width.

As seen in Fig. 3 the wider sash bar 1, 2 is cut away at 6 to allow the narrower sash bar 3, 4 to pass therethrough. It will be noticed that parts of the flanges 2, 2 have been cut away.

Fig. 4 shows a narrower sash bar 3, 4 passed through a wider sash bar 1, 2.

A modified form of the wider sash bar is shown in section in Fig. 6, in which the flanges 7, 7 are curved, that is to say bent towards each other and are connected to a web 8. The edges of the flanges 7, 7 and part of the web 8 are cut away, as shown in Fig. 14, with an aperture 6 similar in shape to that shown in Fig. 3 to allow a narrower sash bar to be passed therethrough.

Fig. 5 is an end elevation of one member of the preferred form of frame employed to carry the sash bars. It consists of three sides 9, 10, 10 at right angles to each other and fitting in its interior the outside faces of the thinner flanges 4, 4 of the narrower sash bars, and also fitting across the ends thereof. The sides 10, 10 are turned inwards towards each other at 11, 11.

The sash bars as shown in Figs. 7 and 8 are grooved at 12, 12 to slide over the inwardly turned parts 11 of the frame. As the wider sash bar 1, 2 will not fit within the frame a portion of each flange 2 is cut away at 13 (Fig. 7) to reduce the width of the end to that of a narrow sash bar 3, 4. In some cases the sash bars may be cut away with inclines 14 as shown in Figs. 11 and 12 so that the reduced ends may be inserted between the in-

wardly turned parts 11. When pressure is applied to the frame member 9, 10 the reduced end will open out the channel and allow the projections 11 to spring into position in the grooves 12.

The frame shown in Fig. 9 is made from two pieces of channel having sections shown in Fig. 5, which pieces are partly cut away at 15, as shown in Fig. 10, to enable the portions of the channel to be bent at right angles to each other to form the mitres 16 of the frame. Two of such pieces are thus bent up and are placed with their straight ends 17 in contact with each other as seen in Fig. 9.

Prior to placing the two ends 17 together the liner 18 is inserted in one of the ends and the other end is passed over the exterior of the liner. The two liners 18 keep the two portions of the frame in alignment.

Such frames with their sash bars are built into hard wood partitions and sashes which retain the two parts of the frames rigidly together and prevent the frame twisting. The partitions and sashes are not shown as they form no part of the present invention.

Some of the sash bars may be as shown in Figs. 7 and 8 and may be slid into the vertical side members of the frame before the two parts thereof are connected together. The sash bars with tapered ends shown in Figs. 11 and 12 are primarily intended to be jumped into the horizontal members of the frame but they may also be slid into the open ends thereof. Before connecting the two parts of the frame together the narrower sash bars are inserted through the apertures 6 in the wider sash bars and the sheets of glass are also inserted.

In the construction shown in Fig. 9 the horizontal sash bars are the wider ones, such as shown in Figs. 6, 7, 11 and 14, and they are slid into the open ends of the vertical members of the frame. The narrower vertical sash bars are as shown in Fig. 12 so that they may be jumped into the horizontal members of the frame.

It will be readily understood that narrower sash bars, such as shown in Figs. 8 and 12, may be slid into the vertical side members of the frame and that wider sash bars, as shown in Fig. 11, may be used vertically and may be jumped into the horizontal members of the frame and such a construction is therefore not shown.

What we claim as our invention is:—

1. An improved glazed frame having two sets of metal sash bars both of I section, both sash bars having channels in the sides of similar width, one set of sash bars having thicker flanges than the other set, the sash bars having the thicker flanges being formed with apertures through which are passed the sash bars having the thinner flanges, a frame of channel section having inwardly turned parts along its open side and grooves in the

sash bars into which the said inwardly turned parts fit, substantially as set forth.

2. An improved glazed frame having two sets of metal sash bars both of I section, both sash bars having channels in the sides of similar width, one set of sash bars having thicker flanges than the other set, the sash bars having the thicker flanges being formed with apertures through which are passed the

10 sash bars having the thinner flanges, a frame of channel section having inwardly turned parts along its open side, grooves in the sash bars into which the said inwardly turned parts fit, and tapered ends on the sash bars 15 to enable them to be forced into the channel shaped frame, substantially as set forth.

3. An improved glazed frame having two sets of metal sash bars both of I section, both sash bars having channels in the sides of 20 similar width, one set of sash bars having thicker flanges than the other set, the sash bars having the thicker flanges being formed with apertures through which are passed the sash bars having the thinner flanges, a frame 25 of channel section to receive the ends of both sets of sash bars, said frame being made in two parts, each part being cut away to enable parts thereof to be bent at a right angle to each other, and liners fitting within the 30 open ends of the two parts of the frame to retain them in alignment, substantially as set forth.

4. An improved glazed frame having two sets of metal sash bars both of I section, both sash bars having channels in the sides of 35 similar width, one set of sash bars having thicker flanges than the other set, the sash bars having the thicker flanges being formed with apertures through which are passed the sash bars having the thinner flanges, a frame 40 of channel section, having inwardly turned edges, to receive the ends of both sets of sash bars, said frame being made in two parts and liners fitting within the open ends of the 45 two parts of the frame, substantially as set forth.

5. An improved glazed frame having two sets of metal sash bars both of I section, both sash bars having channels in the sides of 50 similar width, one set of sash bars having thicker flanges than the other set, the sash bars having the thicker flanges being formed with apertures through which are passed the sash bars having the thinner flanges, a frame 55 of channel section, having inwardly turned edges, to receive the ends of both sets of sash bars, the ends of said sash bars being transversely grooved and cut away with inclines at their ends to enable them to be forced into the 60 frame, substantially as set forth.

6. An improved glazed frame having two sets of metal sash bars both of I section, both sash bars having channels in the sides of same width to fit the glass, one set of sash 65 bars having thicker flanges than the other

set, the sash bars having the thicker flanges being cut away to accurately fit the sash bars having the thinner flanges, these latter bars being passed through said apertures, and a channel shaped frame to receive the ends of 70 both sets of sash bars within the channel, substantially as set forth.

In witness whereof we have hereunto set our hands.

ALBERT de BOIS SHROSBREE.
